ANCHOR

John K. Northrop, Los Angeles, Calif.

Application: March 31, 1941, Serial No. 386,059

15 Claims. (Cl. 114—208)

My invention relates to anchors, and more particularly to lightweight anchors which will plane into bottom, and develop a holding power substantially independent of anchor weight.

Among the objects of my invention are:

To provide a lightweight anchor of relatively high holding power; to provide a lightweight anchor developing a high holding power by virtue of planing action under the stress of a cable pull; to provide a stable anchor; to provide an anchor wherein the stock is a portion of the fluke and aids in the development of the holding power of the anchor; to provide a split fluke anchor forming a dihedral angle under a cable pull, in order to stabilize the anchor; to provide an anchor having a fluke attached to a stock at an angle thereto under a cable pull, which will translate the forward pull into a planing motion, imbedding the anchor into the bottom; to provide an anchor maintaining an efficient planing angle tending to progress the anchor deeper into the bottom as the cable pull increases; to provide an anchor having an extensive fluke area with a shank attached adjacent the center of pressure of the fluke, when imbedded in bottom; to provide an anchor that is cheap to manufacture, has great structural strength for a given weight, and which has a highly effective application of structural material, and to provide an anchor where all of the weight is distributed between a fluke area which is equally effective regardless of how the anchor may fall on the bottom, and a shank member which is stressed primarily only in tension with a secondary and comparatively small stress exerted as a bending moment to keep the flukes at the proper planing angle, and to provide an improved type of anchor wherein all the parts are designed to facilitate bottom penetration.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not limit myself, in any way, to the apparatus of the present application, as I may adopt various other apparatus embodiments, utilizing the method, within the scope of the appended claims.

In the drawings:

Fig. 1 is a top view in elevation of one preferred form of my invention.

Fig. 2 is a side view partly in section and partly in elevation of the anchor of Fig. 1.

Fig. 3 is a rear view in elevation of the anchor of Fig. 1.

Fig. 4 is an angle diagram showing preferred angular relationships of the anchor parts.

5 Figs. 5, 6, 7, 8 and 9 are diagrams showing fluke shape modifications.

Figs. 10, 11, 12, and 13 are diagrammatic side views in elevation showing the behavior of the anchor of Fig. 1 during planing into penetrable bottom.

10 Fig. 14 is a rear view of the anchor of Fig. 1 resting on bottom prior to penetration and in the position shown in Fig. 10.

Fig. 15 is a rear view in perspective of the 15 anchor positioned in Fig. 12.

Fig. 16 is a cross sectional view of the anchor shank, taken as indicated by line 16—16 in Fig. 1, slight enlarged.

In the prior patent issued to myself and Harry 20 M. Gesner, No. 2,075,827, dated April 6, 1937, a lightweight anchor was described and claimed, which has an exceptionally high holding power with respect to the weight of the anchor. This anchor in one preferred form was characterized by the use of a fluke of thin section attached to a shank in such a manner that the fluke presented its tip to bottom when lying on the bottom, with a fluke angle to bottom of approximately 60°. This fluke was maintained at an angle of 25 approximately 25° to 26° to the shank axis line and consequently to the bottom line when the shank was parallel to bottom after penetration 30 of the fluke thereinto. Thus during penetration the angle of the fluke to the bottom plane changed from 60° at the start to 25°—26°, at full penetration, with intermediate angles occurring as more and more of the fluke area entered the bottom. The holding power of an anchor built in accordance with the previous application above referred 35 to, is high and will vary somewhat in accordance with the thickness and area of the fluke and in accordance with the resistance to downward travel of the anchor parts, to give weight to holding power ratios of over 1:200.

40 The anchor of the present invention is illustrated as a divided, balanced fluke anchor and is an improvement on the former anchor in that my present anchor is capable of practically unlimited penetration into bottom. As a consequence, any increase of cable pull on the anchor tends to bury the anchor still deeper because of the planing action thereof. This result is accomplished broadly by attaching the shank adjacent and preferably just above the effective center of pressure of the fluke sections, and by hold- 45 50 55

ing the flukes under a cable pull at a proper planing angle of 40° to 45° thereafter. Thus a cable pull on the opposite end of the shank and in the direction of shank extent will cause the fluke to progress into bottom along a plane substantially 40° to 45° to the line of cable pull. This means that the anchor including the shank may become completely buried in the ground, and that the shank may even be at an angle to the bottom plane, but as long as this latter angle does not exceed an angle placing the fluke in position to plane upwardly, the anchor will progress into the ground. When the shank is raised to an angle of 40° to 45° to the bottom plane, the fluke then becomes parallel to the bottom plane and any increase in this shank-bottom angle will cause the fluke to rise toward the ground to meet the bottom level. Thus the anchor, merely by pulling on the shank at an upward angle to the shank, may be made to plane out of the ground in order that it may be quickly released or broken out of the bottom when desired.

I have also found that it is desirable to laterally extend the upper portions only of the fluke sections. These portions will act as a stock. All of the stock portion of a section is preferably in the same plane as the remainder of the fluke section and therefore aids in the planing action. Furthermore, I have found that when using a divided fluke anchor, with a central shank, that by hinging the fluke sections with relation to each other a dihedral angle can be maintained between them, this dihedral angle being highly efficient in preventing the anchor from twisting, rotating, or cork-screwing out of the bottom, a common failing of prior anchors. I have found an efficient dihedral angle is a total angle of 30° from a straight line passing through the anchor crown, or 15° for each fluke.

Having described my invention broadly, other points will be brought out more in detail by direct reference to the drawings.

Referring to Figs. 1, 2, and 3, a shank 1 preferably of cast steel or bronze is provided at one end with a cable attachment 2, and at the other end with a pin aperture carrying a hinge pin 3. Pin 3 is carried by a yoke 4, this yoke being one end of a forged and machined taper pin 5. Mounted on taper pin 5, by means of spaced hinge lugs 6 and 7, is a fluke section 8. Also mounted on taper pin 5 on hinge lugs 9 and 10 is an opposite fluke section 11, lugs 6 and 7 and 9 and 10 being offset and taper bored to fit alternately on pin 5, these sections being held thereon by end nut 12. The fluke sections are free to rotate on taper pin 5 within a predetermined range as will be explained later. The inner edge of each fluke section is provided with a tapering stiffening rib 14 extending parallel to and closely adjacent shank 1, and each fluke terminates in a penetrating point 15 at the end of stiffening rib 14 in order that a proper section engagement of relatively hard bottom may be obtained. The forward edge of the fluke sections are preferably sharpened for best penetration.

Adjacent the crown of the anchor each fluke section is provided with oppositely disposed crown bosses 16 and 17, these bosses being close to lugs 6, 7, 9 and 10, and extending generally at right angles to the plane of the fluke sections. These bosses 16 and 17 are preferably of thinner section in the direction of ribs 14, and are opposed on each side of each fluke section so that contact of the ends of either bosses 16 or bosses 17 in accordance with rotation of the fluke sections

on pin 5 fixes the dihedral angle during the action of the anchor at approximately 15° for each fluke, as measured to a plane through the hinge line of the fluke hinge and disposed symmetrical to both fluke sections.

The top of each fluke section extends laterally to terminate in relatively narrow portions 20, coplanar with the remainder of the fluke, these extensions acting together to give a stock action to the anchor in order to insure that the anchor will lie flat on the bottom when thrown overboard from a vessel or vehicle.

Shank 1 is free to rotate on hinge pin 3 but is limited in the amount of rotation by shank-end shoulders 21 on either side of pin 3, these shoulders on either side coming to rest against flat surface 24 forming the bottom of yoke 4, and I prefer that the angle be close to the range of from 40° to 45° on either swing of the shank 1, or 80° to 90° total swing.

Before proceeding with the description of the action of the anchor in bottom, it is believed advisable to point out just why certain angles are desirable in the anchor of my invention. I propose to discuss the anchor first as if the fluke were held in coplanar relationship so that the combined sections act as a single fluke, and in the same plane, thus eliminating any dihedral relationship. Under these conditions the most efficient planing and holding angle is obtained when the pull is applied to the fluke at or near the center of pressure, at an angle of 40° to 45° . The center of pressure is defined as being the point of application of all the actual pressure forces acting on the fluke surfaces during penetration. At 45° approximately 70 per cent of the forward pull is translated into a downward moment along the plane of the fluke, and the area of the fluke, as projected along the line of pull, is sufficiently large to provide good holding power once the fluke is embedded. At lesser angles than 45° the downward progression is less even though the moment is greater. The projected area of the fluke in the direction of pull at angles less than 45° will, of course, be smaller. Theoretically, at angles larger than 45° the percentage of forward pull translated into downward movement becomes less and less, although the effective area of the fluke normal to the direction of pull becomes larger as the fluke approaches a 90° angle with the shank, at which point all downward moment would theoretically cease.

In practice the downward movement would cease before the 90° fluke shank angle is reached because the frictional component of the average bottom will prevent penetration if the angle of pull is substantially greater than 60° . The basic reason that my anchor is able to plane into the bottom is that the fluke angle is such that the coefficient of friction does not prevent such planing, whereas in ordinary anchors, this coefficient of friction is opposed to planing action.

It is desired in the present anchor that the anchor shall at all times maintain an efficient planing angle. When the fluke is buried and under a cable pull, it also is highly desirable that the shank be attached to the fluke adjacent the center of pressure, and held with relation to the fluke at a planing angle as close to 45° as is practicable considering other factors which present themselves in a practical anchor. For example, in a balanced anchor such as has been described above, with fluke area on both sides of the shank-fluke hinge line, it is advantageous to hinge the shank to the fluke with the effective center of

pressure between the shank-fluke hinge line and the fluke point, but with the effective center of pressure close to the hinge line, in order that there may be slightly greater pressure exerted on the fluke point side of the hinge line, than on the opposite side of the hinge line, in order that the anchor may never have any tendency to jack-knife or close up with the fluke sections in the plane of the shank. From a practical point of view, therefore, I have found that it is advantageous, for example, in the anchor illustrated, to attach the shank to the effective fluke so that a maximum angle of 40° is obtained, and placing the shank attachment close to the effective center of pressure. This places the stress on the shank almost wholly as tension, only a small bending moment being needed to keep the fluke sections open.

However, I would like to point out that the center of pressure cannot be determined for ordinary bottoms in terms of area times lever-arm length on the fluke portions above and below the hinge line, because the pressure exerted against the fluke in bottoms is not evenly distributed over the fluke area. Weight operated anchor theory is based on the rough, and approximately correct, assumption that holding power varies directly with the depth of penetration. This theory accounts for the fact that the holding power of weight type anchors varies approximately with weight for a given series of geometrically similar weight anchors. From a practical standpoint therefore the pressure exerted on the fluke of the anchor of my invention during penetration would always be greater at the point of fluke than at the crown of the anchor, and this differential in pressure is sufficiently great to maintain the center of pressure below the hinge line even though the geometrical center of pressure calculated with uniform pressure over the entire fluke may be located at times at the crown side of the hinge line. All that is necessary therefore, is that the shank-fluke hinge line shall be located adjacent the actual center of pressure as developed in bottom, but with the effective center of pressure preferably located between the shank-fluke attachment and the digging ends of the fluke section, irrespective of where the calculated, geometrical center of uniform pressure is, with respect to the shank-fluke hinge line. The center of area of the fluke sections need only be approximately determined, and can be readily found by inspection. As the effective center of pressure is, when the anchor is buried, moved slightly toward the digging ends of the fluke sections from the center of area, as above explained, the approximate location of the effective center of pressure can also be determined by inspection.

In the design of my described anchor, or in the design of variations in fluke shape of my anchor, the fact that the anchor does not jack-knife, or close up the flukes parallel to the shank will of course indicate that the actual center of pressure as the anchor is being used, is below the hinge line. I would also like to point out that by placing the actual shank attachment at a hinge line only slightly removed from actual center of pressure as the anchor is being used, the stress on the shank is almost wholly tension, and that the bending moments existing in the anchor parts are small, and need only be sufficient to cause the flukes to remain in planing position with relation to the shank during use.

Thus the weight and bottom resistance of fluke

arms is eliminated and all structural weight is concentrated in one useful fluke area and in one structural member which combines the function of holding the flukes at the proper angle to the line of pull, and connecting that line of pull to the flukes. Unlimited penetration is thereby accomplished.

One other feature is also important, which relates to the shank length, and with fluke length.

When the anchor starts to penetrate into the ground, resting on the fluke points and the cable attachment end of the shank, it is desirable that the angle of the fluke to bottom be not in excess of 60° in order that penetration may be readily started. As the frictional resistance to penetration at angles in excess of 60° increases so rapidly as to prevent proper penetration I therefore prefer to adjust the shank length with relation to fluke length to bring the anchor at or near that initial angle. In the anchor illustrated, the maximum fluke-shank angle is 40° . A line drawn from the cable attachment end of the shank to the center of pressure as found to exist in ordinary bottoms makes an angle with the fluke of 45° , thus placing the effective pull exactly on the center of pressure at that angle; and the line drawn from the cable attachment end of the shank to the points of the fluke sections makes an angle with the fluke of approximately 56° . This anchor has a ready initial penetration and a continued planing action under a cable pull, with the desired bending moment necessary to keep the flukes open.

The use of a dihedral angle in the composite fluke does not change the relationships outlined above, as both fluke sections are planar. The dihedral reduces the effective fluke section area normal to the line of cable pull slightly and this feature is utilized to stabilize the anchor. Thus, if the anchor tends to rotate, the effective area of the rising fluke section normal to the line of cable pull becomes greater and the area of the falling one less, and the rising section thus offers more holding power than the opposite fluke section, thus counteracting the turning movement and returning the anchor to a central position, exactly as occurs in airplanes when a dihedral angle is used between two wing sections to stabilize the machine.

Having thus described the structure of the anchor and pointed out the advantages of certain angular relationships of the parts thereof, I will now describe the action of the preferred form of anchor in bottom.

Referring to the diagrams in Figs. 10 to 13, inclusive, and beginning with Fig. 10 showing the manner in which the anchor behaves on first reaching the bottom, the anchor may be provided with a cable 30 attached to the shank 2 of the anchor and the anchor thrown overboard to lie on bottom 31. The anchor will then assume the position shown in Figs. 10 and 14. Before any pull is applied, the points 15 of the flukes, the ends of the stock portions of the flukes and the end of bosses 16 or 17 will rest on bottom together with the end of the shank, irrespective of which side up the anchor happens to fall. As the pull is applied to the shank, in line with the general direction of the shank, the ends of the bosses 16 or 17 penetrate the bottom to some extent as do the ends of the stock portions 20 and as the anchor starts to move they produce a pitching moment which throws points 15 into bottom where they catch. The fluke sections then hinge with respect to the shank on the fluke

shank pivot 3 as shown in Fig. 11 until the shank reaches its maximum permitted angle to the flukes. At this time the dihedral angle may also be present because the weight of the stock sections 20 may rotate fluke sections 8 and 11 on pivot 5. The anchor then planes into bottom as shown in Fig. 12. In this figure the shank is shown just ready to enter bottom with the ends of the stock portions 20 touching the ground. The dihedral angle under the forward pull is now fully held at its maximum, and the rear bosses 16 or 17 as shown in Fig. 15 are touching to maintain this angle. Under a continued forward pull the anchor continues to plane into the ground even though the shank may assume an angle with the bottom plane, and the fluke sections may become completely buried in the ground. However, a stronger pull will force the fluke still further into the ground, and under an extremely heavy pull the entire anchor including the shank and stock portions of the fluke may become buried, thereby developing an exceptionally high holding power, the dihedral angle at all times protecting the anchor against rotation. As long as the shank does not exceed an angle of 40°:45° with the bottom plane, there will be no tendency for the anchor to come out of the bottom. Thus, increase in forward pull creates downward movement of the anchor, and the resultant downward movement of the anchor increases its holding power. I have, for example, made experiments with a ten pound anchor wherein the shank and fluke sections are of cast steel, the flukes being of thin sections and of the same contour as shown in the drawings, with a shank-fluke angle of 40°, with a shank length sufficient to give a 56° angle with a line connecting the cable end of the shank with the points of the fluke, and found that this anchor will develop a holding power of in excess of 4,500 pounds. Repeated experiments have shown that a weight-to-holding-power ratio of at least 1:500 may be readily obtained. Increased holding power of my anchor may be attributed to efficient distribution of weight and unlimited penetrating power due to the fact that the fluke is maintained at all times after penetration at an efficient planing angle.

In Figs. 5 to 8, inclusive, I have shown various modifications of fluke shape which may be used in conjunction with the anchor of my invention. The fundamental basis of all of these shapes is that the digging end of the fluke shall be relatively sharp-pointed with a gradual increase in width, the fluke section having its maximum width at the crown end. There will be some variation in the positions of the effective centers of pressure when using fluke sections of different contour, as it will be obvious that different fluke section shapes may shift the center of pressure slightly toward or away from the crown of the anchor. Such a shift in the effective center of pressure, however, is not important unless the shift would bring the hinge line of the shank on the point side of the effective center of pressure in which case the anchor would of course have a tendency to close up with the flukes parallel to the shank. However, this may be avoided when using such a fluke section shape by moving the hinge line toward the crown of the anchor so that the effective center of pressure is always relatively close to and below the hinge line. It will be obvious from an inspection of Figs. 5 to 9, inclusive, that certain of these anchors have greater actual fluke section area than others and this change in area may be very effectively

utilized for anchors designed for special purposes. For example, an anchor with the fluke section shape of Fig. 6 may be utilized in relatively hard bottom with good penetration and consequent good holding power, wherein a fluke section shape such as shown in Fig. 9, may be utilized in relatively soft muddy bottom in order to give greater holding power and greater planing ability.

The shapes shown in Figs. 7 and 8 are intermediate in area between the sections shown in Figs. 8 and 9. The type of fluke area shown in Fig. 5 may be utilized when it is advisable to use a relatively short effective stock, and where it is desirable that the effective center of pressure be well toward the points of the fluke sections. The features common to all the shapes shown are that the points of the fluke sections are sharpened and closely adjacent the shank plane, that the opposite edges of the fluke section are extended laterally to insure the anchor lying flat on bottom, and that the effective center of pressure of the combined fluke sections be kept relatively close to and preferably on the point side of the shank hinge line. I do not therefore wish to be limited to any particular fluke section shape as it will be obvious to those skilled in the art that by following the teachings given herein, almost innumerable fluke shapes will be satisfactory for various purposes as desired. In that regard I have found that the shape shown in the anchor of Figs. 1 to 3, inclusive, is a satisfactory compromise for use in hard, medium, and soft bottoms. The fluke section shape has the sharp points for initial penetration, relatively slow flaring of the fluke section near the point, with the gradual lateral extension of the sides of the fluke sections into the stock portions 20. Such an arrangement places the larger part of the actual area of the fluke close to the shank plane with the effective center of pressure close to the hinge line to keep the flukes open under all circumstances.

It is to be noted that all parts of my anchor are designed to facilitate complete penetration beneath the bottom plane. The flukes are of thin section and present little resistance to the bottom material. Crown bosses 16 and 17 are streamlined in the direction of penetration to reduce penetration resistance, and the entire stock surface opposed to bottom is reduced to the minimum. Thus the anchor planes readily into and beneath the bottom without resistance which would be caused by extended surfaces opposed to the line of penetration movement.

I claim:

1. An anchor comprising a shank, a cable attachment at one end of said shank, and a fluke having a digging end and an opposite end, said shank being attached to said fluke intermediate the ends thereof at a point closely adjacent the effective center of pressure developed on said fluke by a cable pull through said shank, when said fluke is completely buried in penetrable bottom, with a fluke-shank angle of approximately 40° to 45°, portions of said fluke being extended laterally on the opposite side of the shank attachment from the digging end of said fluke along substantially a smooth curve, to form an effective stock.
2. An anchor comprising a pair of substantially planar fluke sections having adjacent long dimensions and outwardly flaring edges, said sections when combined forming a symmetrical split fluke, a hinge pin extending between the adjacent

edges of said fluke sections adjacent the wider portions thereof, hinge bearings on each of said sections and engaged by said hinge pin, means for limiting the rotation of said fluke sections relative to each other around said pin as an axis, a shank rotatively connected to the lower end of said hinge pin, and means for limiting the rotation of said shank with respect to said hinge pin.

3. An anchor comprising a shank, a fluke section attached on each side of said shank, with a rotation stabilizing dihedral angle of approximately 15° of said fluke sections under a cable pull.

4. An anchor comprising a pair of fluke sections having adjacent edges and connected between said adjacent edges by a hinge, a shank attached to both of said sections on the line of said hinge, and cooperating stop means limiting the relative movement of said fluke sections to a rotation stabilizing dihedral angle for each section as measured to a plane through the line of said hinge and disposed symmetrical to said fluke sections.

5. An anchor comprising a pair of fluke sections having adjacent edges and connected between said adjacent edges by a hinge, a shank attached to both of said sections on the line of said hinge, and cooperating stop means limiting the relative movement of said fluke sections to a rotation stabilizing dihedral angle of approximately 15° for each section as measured to a plane through the hinge line of said hinge and disposed symmetrical to said fluke sections.

6. An anchor comprising a pair of fluke sections having adjacent edges and connected between said adjacent edges by a hinge, a shank attached to both of said sections by a second hinge on the line of said first hinge, cooperating stop means limiting relative movement of said fluke sections to a symmetrical dihedral angle of approximately 15° for each section as measured to a plane through the hinge line of said hinge and disposed symmetrical to said fluke sections, and additional stop means cooperating with said shank and fluke sections to limit rotation of said fluke sections on said second hinge to 40°-45° on either side of said shank.

7. An anchor comprising a pair of fluke sections having adjacent edges, having hinge bearings mounted thereon, a hinge pin passing through said hinge portions hingedly connecting said fluke sections, stop means limiting rotation of said fluke sections on said hinge pin to opposite and equal dihedral angles on each side of a common fluke section-hinge pin plane, a shank having a cable attachment at one end thereof, a second hinge joining said hinge pin and the other end of said shank intermediate the extent of the adjacent edges of said fluke sections, and additional stop means limiting relative rotation of said hinge pin and said shank to equal angles on each side of the coextensive position thereof.

8. An anchor in accordance with claim 7 wherein said stop means are respectively proportioned to hold said anchor when embedded with said fluke sections at a dihedral angle of approximately 15°, and with said hinge pin at an angle to said shank of from 40° to 45°.

9. An anchor in accordance with claim 7 where-

in said fluke sections are provided with digging ends and wherein the ends of said fluke sections on the opposite side of said hinge pin-shank attachment are extended laterally in the general plane of each fluke section to act as stock portions.

10. An anchor comprising a shank, a cable attachment at one end of said shank, a fluke section on each side of said shank, said fluke sections being connected together and to the other end of said shank, said shank connection being adjacent the effective center of pressure as developed on the combined area of both of said sections under a cable pull when buried in penetrable bottom, means for holding said fluke sections at an angle of approximately 40° to 45° to the shank when so buried, said fluke sections being connected together by a hinge, and means for limiting the relative rotation of said fluke sections on said hinge to provide a rotation stabilizing dihedral angle on said fluke sections when under said cable pull in bottom.

11. An anchor comprising a shank, a cable attachment at one end of said shank, a fluke section on each side of said shank, said fluke sections being hingedly connected together and to the other end of said shank, said shank connection being adjacent the effective center of pressure as developed on the combined area of both of said sections when buried in penetrable bottom, and means for limiting the relative rotation of said fluke sections on said hinge to provide a rotation stabilizing dihedral angle on said fluke sections of approximately 15° when under cable pull.

12. An anchor comprising a shank, an extension hingedly secured at one end of said shank, and a fluke hingedly secured to said extension for movement normal to the movement of said shank.

13. An anchor comprising a shank, an extension hingedly secured at one end of said shank, a pair of substantially planar flukes hingedly secured to said extension, said flukes being capable of occupying a common plane, means for limiting the hinge movement of said shank with respect to said extension to a predetermined angle on either side of said common plane, and means for limiting the hinge movement of each fluke to a predetermined angle on either side of said common plane.

14. An anchor in accordance with claim 2 wherein said fluke section limiting means limits the relative rotation of the two fluke sections to substantially 60° and wherein said shank limiting means limits said shank rotation with respect to said hinge pin to approximately 40° to 45° on each side of said shank.

15. An anchor in accordance with claim 2 wherein said fluke section limiting means limits the relative rotation of the two fluke sections to substantially 60° and wherein said shank limiting means limits said shank rotation with respect to said hinge pin to approximately 40° to 45° on each side of said shank, and wherein the length of said fluke sections and the length of said shank are coordinated to provide an initial fluke penetration angle of approximately 60° under a cable pull.

JOHN K. NORTHRUP.
